US0D1070765S

(12) **United States Design Patent** (10) Patent No.: **US D1,070,765 S**
(45) Date of Patent: ** Apr. 15, 2025

(54) **INVERTER**

(71) Applicants: **HICONICS ECO-ENERGY DRIVE TECHNOLOGY CO., LTD.**, Beijing (CN); **HICONICS ECO-ENERGY TECHNOLOGY CO., LTD.**, Beijing (CN)

(72) Inventors: **Zhiyong Zhao**, Beijing (CN); **Song Gao**, Beijing (CN); **Jietao Gao**, Beijing (CN)

(73) Assignees: **HICONICS ECO-ENERGY DRIVE TECHNOLOGY CO., LTD.**, Beijing (CN); **HICONICS ECO-ENERGY TECHNOLOGY CO., LTD.**, Beijing (CN)

(**) Term: **15 Years**

(21) Appl. No.: **35/520,989**

(22) Filed: **Apr. 25, 2024**

(80) **Hague Agreement Data**

Int. Filing Date: **Apr. 25, 2024**

Int. Reg. No.: **DM/237062**

Int. Reg. Date: **Apr. 25, 2024**

Int. Reg. Pub. Date: **May 24, 2024**

(30) **Foreign Application Priority Data**

Primary Examiner — Derrick E Holland

(74) Attorney, Agent, or Firm — Scully, Scott, Murphy & Presser, P.C.

(57)

CLAIM

The ornamental design for an inverter as shown and described.

DESCRIPTION

1. Inverter
- 1.1 : Perspective
- 1.2 : Perspective
- 1.3 : Front
- 1.4 : Back
- 1.5 : Left
- 1.6 : Right
- 1.7 : Top
- 1.8 : Bottom

(Continued)

FIG. 1.1 to FIG. 1.8 show an inverter to embodiments of the present design, respectively.

1 Claim, 8 Drawing Sheets
